RESILIENT PRESS COVER ASSEMBLY
Arvid B. Anderson, Park Ridge, Harvey L. Davis, Highland Park, and Roy M. Schultz, Chicago, Ill., assignors to Bishop Freeman Co., a corporation of Illinois
Filed Sept. 19, 1966, Ser. No. 580,351
13 Claims. (Cl. 38—66)

This invention relates to resilient types of press covers and press cover assemblies, and particularly to those adapted to be used in opposing paired relation on dry cleaning presses, laundry presses and on presses used in garment manufacturing processes. The press covers of this invention are adapted for use on the pressing members, sometimes known as the head and the buck of such a press, and the press cover assembly of this invention is constructed, where desired, to be generally symmetrical in that all regions of the pressing surfaces exhibit comparable resilience and surface characteristics.

In the present disclosure, the pressing surface of each of the opposed press covers is provided with a steam permeable, non-uniform coating of a temperature resistant plastic such as polytetrafluoroethylene, thereby presenting opposed surfaces which are of high lubricity, which surfaces facilitate the pressing of opposite garment surfaces without imparting pattern and shine thereto. Furthermore, the press covers of this invention are substantially more heat and moisture resistant than prior art press covers, making possible the use of such press covers on the upper pressing member or head of a press.

Special purpose press covers are known in the art, one example thereof being illustrated in Freeman Patent No. 2,814,135. Such covers have been developed to avoid certain objectionable aspects of rigid press plates, such as metallic press plates. Covers of the type depicted in said patent exhibit a certain degree of resilience and compressibility, thereby to receive garment projections, such as buttons, zippers, seams and the like, to permit a full surfaced pressing action. This invention is directed toward improvements in the type of press covers described in said patent.

The present invention provides a cushioned press cover for use on each of the pressing members of a press. Together, the press covers for the pressing members, i.e., for the buck and the head, constitute a unique press cover assembly of improved properties and characteristics, providing a total pressing action characterized by uniformly cushioned lubric plastic surfaces acting in opposing relation. Each of the press covers comprises a multi-layer assemblage, arranged to impart a soft, safe, shineless finish, with a minimum of pattern, to all types of fabrics and garments, while substantially eliminating impressions resulting from garment associated buttons, zippers, seams and the like. Each of the layers retains its individual properties, the layers collectively providing a long lasting, wear and heat-resistant assemblage.

In the disclosed embodiment, the press cover for the upper pressing member or head includes a perforate non-stretchable diffusor layer, such as a metallic plate, which carries a plurality of further layers and which determines the actual contour of the press cover. The further layers are of special purpose materials which individually and collectively are steam-permeable and which collectively cushion and thermally insulate the contact or pressing surface of the press cover. To that end, the plurality of layers includes an inner layer of asbestos fabric, an intermediate layer of a compressible fibrous material and a surface layer. In the present embodiment, the intermediate layer is integrally formed from the surface layer. The surface layer is coated with a non-uniform steam permeable layer of polytetrafluoroethylene to provide a

2

pressing surface which is highly lubric whereby in use the press cover will impart a minimum of shine to a garment pressed.

The press cover for the lower pressing member or buck is generally symmetrical with that for the upper pressing member and to that end comprises a multi-layer assemblage, the materials of which may be the same except that the non-stretchable layer is preferably of a fabric rather than of the metal previously referred to. That fabric is, as stated, relatively non-stretchable so that it will define and maintain a predetermined shape for the multi-layer assemblage of which the press cover is made.

These and other advantages, characteristics and purposes of this invention will be apparent from the following description and drawings of which:

FIGURE 1 illustrates a garment press to the pressing members of which press covers have been secured;

FIG. 2 is a partial sectional view taken substantially along the line 2—2 of FIG. 1;

FIG. 3 is a partial sectional view taken substantially along the line 3—3 of FIG. 1;

FIG. 4 is a bottom fragmentary view of FIG. 2 with certain portions broken away for convenience of illustration; and

FIG. 5 is a plane view of FIG. 3 with certain portions broken away for convenience of illustration.

Referring now to the drawings, FIGURE 1 illustrates a typical press 1 with which the press cover assembly of this invention is adapted to be used. The upper pressing member 10 is frequently referred to as the head and the lower pressing member 12 as the buck. The head and the buck are hingedly connected along a hinge axis defined by hinge 14, about which the head is movable downwardly towards the buck, as by handle 16. Press 1 is suitably supported at a desired elevation, as by table 18. Head 10 includes a steam chest (not shown) to which steam is supplied, usually at 50 to 100 p.s.i., from a suitable source such as a steam generator. The lower surface of the head is generally provided with a plurality of perforations (not shown) through which steam discharges downwardly toward an object to be pressed as the head and buck are brought into a juxtaposed pressing relationship.

The press cover assembly comprises press covers 22 and 24 for the head and the buck, respectively. As seen in FIG. 1, head cover 22 conforms to head 10, covers its entire pressing surface and extends upwardly to surround at least a portion of the peripheral edge of the head. The upwardly extending flange 26 of cover 22 circumscribes and lies closely parallel to the peripheral edge of the head. Head cover 22 is suitably attached to the head as by coil springs 30 which are secured at their ends to flange 26 and which overlie head 10.

As seen in FIGS. 2 and 4, head cover 22 is multi-layered and includes a relatively non-stretchable, steam-permeable layer which, as shown in FIG. 2, is a perforate metallic plate 32 defining a plurality of multi-directionally oriented, apertured, upwardly extending projections 34. Plate 32 may be aluminum and may be constructed in accordance with U.S. Patent No. 2,880,529. Steam issuing through the perforations of the head is directed in a plurality of directions as it enters the openings of apertured projections 34 thereby tending to diffuse the steam emitted by the head over the entire press cover in a substantially uniform fashion.

Immediately adjacent plate 32 is an inner layer of a porous, heat-resistant material, such as asbestos cloth 35. The asbestos cloth inner layer thermally insulates the remaining layers from the non-stretchable head contacting plate 32 and is sufficiently porous to allow the steam issuing from the head to pass therethrough.

The next layer, the cushion layer 36, is also steam-

permeable and comprises a compressible but resilient heat and steam-resistant material such as a napped nylon flannel 38 which may be integrally formed with the pressing surface layer 40 which in turn is stretchable and comprises a filament type of knit nylon fabric. The napped nylon is formed from the surface layer 40 by a napping process that draws out the filaments to form the flannel 38. The nap is compressible but highly resilient in press cover usage and is of a substantially greater thickness than surface layer 40. The knit nylon surface layer 40 is abrasion and heat-resistant, hence is long wearing. Since the knitted and napped portions, respectively, of the cushion layer 36 are stretchable and resilient, the cushion layer 36 accommodates cover distorting forces resulting from the presence in a garment to be pressed, of buttons, 10 zippers, seams and the like, thereby providing a full surfaced pressing action without significant marking of the garment pressed.

To enhance the wear resistance of cover 22 and to improve the quality of the press given to a garment, layer 40 is provided with a porous or non-uniform layer of polytetrafluoroethylene, as by spraying layer 40 to form, on the knit portions of the filaments defining the pressing surface, a non-uniform porous polytetrafluoroethylene coating which is represented by the dotted line 42 in FIG. 2 and by the enclosed spaced apart areas in FIG. 4.

The head cover 22 incorporates a peripheral flange 26 which receives the peripheral edge of the head 10. The marginal portions of the layers of cover 22 which comprise flange 26 are suitably interconnected or secured to each other either by a high temperature adhesive (not shown), or by mechanical fasteners such as grommets, rivets or the like (not shown).

The buck cover 24 is generally symmetrical with head cover 22. Cover 24 is of a multi-layer construction defining a major buck covering portion which overlies buck 12 and a marginal portion which embraces the peripheral edge of the buck. Securance of the marginal portion to the buck to attach cover 24 to buck 12 may be accomplished by utilizing a draw string arrangement movable within a looped marginal portion of cover 24 (not shown) in a manner similar to that illustrated in the aforementioned Freeman Patent No. 2,814,135.

As seen in FIGS. 3 and 5, the multi-layer construction of press cover 24 includes a relatively non-stretchable steam-permeable liner such as a porous woven fabric 54. Woven fabric 54 is steam permeable so that it will admit the steam to the buck. Adjacent to fabric layer 54 lies a porous heat-resistant material, such as asbestos cloth 52. Preferably, asbestos cloth 52 lies against the buck. A 50 porous cushion layer 56 (similar to cushion layer 36), including a surface layer 58 which may be of the same stretchable material as surface layer 40, is provided. Each of the buck cover layers is secured at its marginal edge to form an integral unit which may then be secured to the buck in the manner described above. The stretchability of layer 58 enhances the snugness of the fit of cover 24 over the buck.

Finally, to enhance the wear resistance of cover 24, and particularly to improve the quality of the press given to an object to be pressed, layer 58 is coated with a non-uniform porous layer of polytetrafluoroethylene 60 of the same steam-permeable characteristics as layer 42.

The press cover assembly of this invention then comprises a pair of press covers, one for each of the pressing members, i.e., the head and the buck. The covers are generally comparable in resilience and surface characteristics to provide corresponding pressing action and each cover comprises a plurality of layers which contribute, individually and collectively, to a desired high quality press to be given to a garment. The pressing layer of each of the covers is desirably provided with a non-uniform or porous layer of a heat resistant plastic such as polytetrafluoroethylene to minimize shine and to enhance the qual-

ity of the press given to a garment by the press cover assembly.

The use of full surfaced uniform press covers provides a type of total pressing action that achieves a superior finish on the completed garment. The pressing action and actual surface finish are particularly characterized by the fact that the entire contacting surface is comprised of uniformly cushion lubric plastic.

Although this invention has been described in part in terms of the embodiments illustrated, it will be apparent to those skilled in the art that modifications may be made without departing from the spirit and scope of this invention.

What is claimed is:

1. A heat and steam-resistant, steam-permeable press cover for a pressing member of a steam press, comprising a non-stretchable layer adapted to lie adjacent a pressing member, a pressing surface layer having a steam-permeable coating of polytetrafluoroethylene, a resilient locally compressible fibrous intermediate layer lying between said non-stretchable layer and said pressing surface layer, means peripherally securing said layers together and to each other and means connected to said press cover for attaching said press cover to a pressing member.

2. The press cover of claim 1 in which said non-stretchable layer is a rigid steam diffusing plate.

3. The press cover of claim 1 in which said non-stretchable layer is a woven cloth layer.

4. A heat and steam-resistant, steam-permeable press cover for a pressing member of a steam press, comprising a non-stretchable layer adapted to lie adjacent a pressing member, a pressing surface layer having a steam-permeable coating of polytetrafluoroethylene, a resilient locally compressible fibrous intermediate layer lying between said non-stretchable layer and said pressing surface layer, means peripherally securing said layers together and means connected to said press cover for attaching said press cover to a pressing member, said pressing surface layer and said resilient layer being integrally formed, said resilient intermediate layer comprising nap drawn from said pressing surface layer.

5. The press cover of claim 4 in which a woven asbestos cloth layer is disposed between said intermediate layer and said non-stretchable layer.

6. The press cover of claim 4 in which said pressing surface layer is a stretchable knit fabric.

7. A press cover assembly comprising a steam-permeable buck cover and a steam-permeable head cover, each of which presents a uniformly cushioned lubric plastic pressing surface as the garment contacting portion thereof, said head cover comprising an inner non-stretchable steam diffusing layer, an intermediate resilient fibrous layer, a pressing surface layer and means for securing said head cover to a press head and said buck cover comprising an inner non-stretchable layer, an intermediate resilient fibrous layer, a pressing surface layer and means for securing said buck cover to a press buck.

8. The press cover assembly of claim 7 in which said pressing surfaces are each provided with a steam-permeable coating of polytetrafluoroethylene.

9. A press cover assembly comprising a steam-permeable buck cover and a steam-permeable head cover, each of which presents a uniformly cushioned lubric plastic pressing surface as the garment contacting portion thereof, said head cover comprising an inner rigid steam diffusing plate, an intermediate resilient fibrous layer, a pressing surface layer and means for securing said head cover to a press head and said buck cover comprising an inner non-stretchable fabric layer, an intermediate resilient fibrous layer, a pressing surface layer and means for securing said buck cover to a press buck.

10. The press cover assembly of claim 9 in which each of said intermediate and pressing surface layers are integral and the intermediate layer is a flannel nap drawn from said pressing surface layer, said nap layer being

substantially thicker than said pressing surface layer.
11. The press cover assembly of claim 9 in which a layer of asbestos cloth is disposed between said inner rigid plate and the adjacent intermediate layer.

12. The press cover assembly of claim 9 in which said pressing surfaces are each provided with a steam-permeable coating of polytetrafluoroethylene.

13. A press cover assembly comprising a steam-premeable buck cover and a steam-permeable head cover, each of which presents a uniformly cushioned lubric plastic pressing surface as the garment contacting portion thereof, each of said pressing surfaces comprising a knit fabric of filaments from which a cushion layer of napped flannel

is drawn, each of said pressing surfaces, being provided with a garment contacting steam-permeable coating of polytetrafluoroethylene.
